UNITED STATES PATENT OFFICE.

OLIVER STANTON HOOVER, OF STANFORD UNIVERSITY, AND MORRIS TALLY HOOVER, OF MOUNT VIEW, CALIFORNIA.

DEVICE FOR GATHERING PRUNES.

SPECIFICATION forming part of Letters Patent No. 654,399, dated July 24, 1900.

Application filed August 16, 1899. Serial No. 727,390. (No model.)

To all whom it may concern:

Be it known that we, OLIVER STANTON HOOVER, of Stanford University, and MORRIS TALLY HOOVER, of Mount View, in the county 5 of Santa Clara and State of California, have invented a new and Improved Device for Gathering Prunes, of which the following is a full, clear, and exact description.

One object of the invention is to provide a 10 durable and economic machine adapted for gathering prunes from the ground after they have fallen from the tree, which result is accomplished through the medium of atmospheric pressure suitably applied.

15 A further object of the invention is to provide a machine of the character set forth that may be attached to a wagon or to any vehicle capable of being drawn along under the trees.

Another object of the invention is to provide 20 a machine for gathering prunes from the ground which will adapt itself to uneven surfaces and will convey the gathered prunes to a suitable receptacle, from which the fruit is delivered to a box or other device for storage 25 purposes.

A further object of the invention is to so construct the machine that it will be automatic in its action with the exception of the 30 pump that is adapted to supply air under pressure and create suction in the fruit-gathering portion of the machine. It will, however, be understood that a motor may be provided for the pump and other mechanically-controlled mechanism be used in connection with the machine.

The invention consists in the novel construction and combination of the several parts, as will be hereinafter fully set forth, and pointed out in the claims.

40 Reference is to be had to the accompanying drawings, forming a part of this specification, in which similar characters of reference indicate corresponding parts in all the figures.

Figure 1 is a side elevation of the improved machine. Fig. 2 is a plan view of the same. Fig. 3 is a detail side elevation of the gathering-head of the machine, illustrating the prunes as received upon a screen and in position to be delivered from the machine. Fig. 45 4 is an enlarged vertical section through a portion of the gathering-head of the machine.

Fig. 5 is a section through the valved portion of the tube adapted to conduct air under pressure to the gathering-head. Fig. 6 is a sectional view through the valved portion of the 55 suction or vacuum pipe adapted for connection with the gathering-head, and Fig. 7 is a longitudinal section through the air-compressing and vacuum device employed in connection with the machine.

60 The device may be attached to a wagon-body A or its equivalent, and the attachment is made through the medium of an articulated beam B, which constitutes the body of the frame of the machine. This articulated beam 65 B is usually made in two sections connected by a suitable pivot 10, and the inner section is attached by a pivot-pin 11 or its equivalent to the wagon-body A. The construction of the frame is completed by securing to the main 70 section of the articulated beam B at each side an upwardly-extending truss 12, usually braced by longitudinal intermediate beams 19, as shown in Fig. 1. A gathering-head C is located at the outer end of the articulated 75 beam B, and this gathering-head C is attached to an upright 13, held to slide in said beam B and also preferably in a hollow bracket 14, secured to the said beam, as is also shown in Fig. 1. The upright 13 is provided with two 80 or more transverse openings 15 and 15^a, either of which openings is adapted to receive a spring-controlled bolt 16, located at the upper portion of the beam B, so that the gathering-head may be securely held in an upper or in 85 a lower position, as may be found necessary. The bolt 16 is connected with a rod 17, and this rod in its turn is pivotally connected with a lever 18, fulcrumed upon a beam 19, forming a portion of one of the sides 12 of the frame, 90 as shown in Fig. 1, and this lever 18 is operated automatically in a manner that will be hereinafter set forth.

95 The upright of the gathering-head C is preferably raised and lowered through the medium of a pitman 20, having a crank-arm 21, that extends through a longitudinal slot 21^a in the upper portion of the upright 13, as shown in Fig. 1, and this pitman is connected by a wrist-pin 22 with a sprocket-wheel 23 or 100 its equivalent, suitably journaled upon an upper extension 24 of the bracket 14. It may

be here remarked that the bolt 16 is located within the bracket 14 and is thus protected from the weather. The sprocket-wheel 23 is driven by means of a driving mechanism that 5 will be shortly described in detail, and the downward movement of the upright 13 is limited by a collar 25, secured to said upright and which engages with the upper surface of the bracket 14.

10 The gathering-head C is of substantially box-like construction and is shown as rectangular in the drawings; but it may be given any other desired shape. In the construction of the gathering-head C a central chamber 26 is provided and an upper chamber or duct 27, the upper chamber or duct 27 being provided with a nipple 28 at its top and with another nipple 29 at one end, the other end of said duct or chamber 27 being closed. At 15 the bottom portion of said gathering-head C a second duct or chamber 30 is formed parallel with the upper chamber 27, and this lower duct or chamber 30 is provided with a nipple 31 at one end and is closed at the opposite end. A series of tubes 32, preferably of metal, extends through the central chamber 26, connecting with the upper and lower ducts 27 and 30, and at the upper end of each tube 32 a screen 33 is preferably located.

20 25 Metal tubes 34 of smaller diameter are secured in the bottom of the gathering-head in vertical alinement with the main tubes 32, and nipples 35, preferably of rubber, are fitted to the lower tubes 34 at their lower or projecting ends, the lower portions of said nipples 35 being open.

30 35 A gathering-tube 36 is located in each of the main tubes 32, and the gathering-tubes are of less diameter than the main tubes 32.

40 45 Said gathering-tubes 36 extend down through the lower guide-tubes 34, moving snugly therein and out beyond the lower ends of the nipples 35, the lower ends of said nipples 35 closely hugging the said gathering-tubes, while at the lower end of each gathering-tube 36 an elastic sleeve 37 is secured, and each sleeve carries a nozzle. Each nozzle preferably consists of an outer metal tube 38, an inner thimble 40, and a strip or piece of linen 45 50 or a like material, that practically closes the nozzle near its lower end and is held in place by the thimble and outer tube 38 of the nozzle, as shown best in Fig. 4. Each gathering-tube 36 is practically closed at its upper end, except that each of said tubes is provided with an aperture 43 at its upper end, and the upper end portion of each gathering-tube is connected by a cord or wire 41 or its equivalent with a piston-head 42, that is 55 60 closely fitted to the inner diameter of the main tube 32, in which the gathering-tube is placed. The tubes are adapted to be raised and lowered pneumatically, as will be herein-after described, and will accommodate themselves to any inequalities of the ground, as 65 shown in Fig. 1, and the nozzle portion of each of the gathering-tubes extending from

the gathering-head is adapted to attract and retain any fruit with which it may contact by reason of a vacuum or suction suitably applied to said gathering-tubes.

70 Each gathering-tube preferably extends downward through a wire net or gauze 46, properly supported at the bottom portion of the gathering-head, as shown in Fig. 3. This 75 gauze serves to guide the lower ends of the gathering-tubes and at the same time prevents any material from packing between the tubes to a great extent, and the screen furthermore acts to hold the tubes 36 steady, as 80 will be hereinafter set forth. Each gathering-tube is provided with what we term a "float-valve" 44, and each float-valve is provided with a disk 45, attached to its upper end, in order that it may be more susceptible 85 to attraction by a vacuum and in order that the upper end of the valve may better close the opening 43 in the upper end of the gathering-tube in which it is located. The valves 44 and disks 45 are of such diameter that 90 they freely move within the gathering-tubes, and usually the valves are elongated and are made of wood.

95 In Fig. 7 an improved pump for compressing air and for creating a suction or vacuum is illustrated in section. This pump consists of a suction or vacuum cylinder D, an air-compressing cylinder E, and a storage cylinder or chamber F for compressed air, and the entire pump is adapted to be placed in the 100 vehicle-body A or other instrumentality employed to carry the machine.

105 The suction or vacuum cylinder D is provided with a head at each of its ends, and in one head two tubes 47 and 47^a are located, and above said tubes a valve 48 is placed opening outwardly. A piston 50 is held to slide in the suction or vacuum cylinder D, and another piston 51 is held to slide in the compressing-cylinder E, and when the piston 110 in the compressing-cylinder is at the end nearest the vacuum-cylinder the piston in the vacuum-cylinder is at a point about central of the same. These two pistons 50 and 51 are connected by a rod 52, which may extend 115 through a suitable gland 53 in what may be termed the "inner" head of the vacuum or suction cylinder, and the said rod 52 is provided with a series of teeth 54 upon its under surface adapted to be engaged by the teeth 120 of a pinion 55, operated through the medium of a hand-lever 56 or its equivalent.

125 One end of the air-compressing cylinder E is open, while the other end is closed. The closed end of the air-compressing cylinder is provided with an inwardly-opening valve 57, as is also shown in Fig. 7, and a pipe 58 extends from the storage-cylinder F into the compressing-cylinder E, being provided with a bend within the compressing-cylinder, and 130 in the bottom of the bent portion of said pipe 58 an upwardly-extending valve 59 is located.

The storage-cylinder F, which is closed at both ends, is provided at one of its ends with

an outlet-tube 60. The outlet-tube 60 of the storage-cylinder F receives one end of a pipe 61, that is adapted to carry the compressed air into the upper portion of the gathering-head C, the said pipe 61 being connected with the thimble 28 at the top portion of said gathering-head. This pipe 61 is provided with a valve 62, and said valve is adapted to be automatically opened and closed. To that end the plug of the valve, as shown in Fig. 5, is provided with a stem 63, which stem receives a shaft 64, on which a bevel-pinion 65 is secured, the said shaft being mounted to turn in a suitable bearing 65^a, secured to an upright 66, as is shown also in Fig. 5. A pipe 67, adapted to create a vacuum or produce suction in the gathering-head, is connected with the tube 47^a, extending from the suction or vacuum cylinder D. This tube 67 is connected, through the medium of the nipple 31, with the main chamber or duct 30 in the gathering-head C. The said pipe 67 is provided with a valve 79, as shown in Fig. 1, the plug of which has a handle 80 attached thereto, the handle being at an angle to the plug, as illustrated in Fig. 1. A second vacuum or suction pipe 68 is connected with the suction or vacuum cylinder D through the medium of the extension 47, and this pipe 68 is connected with the upper duct or chamber 27 of the gathering-head through the medium of the nipple 29. The pipe 68 is provided with a valve 69, (shown in detail in Fig. 6,) and the plug of this valve 69 is provided with a stem which is connected with a shaft 70, journaled at one end in a bearing 71, attached to an upright 72, as shown in Figs. 1 and 6, and said shaft is provided between its ends with a crank-arm 73. The said shaft 70 at its opposite end carries a bevel-gear 75, corresponding to the gear 65 of the valve 62 heretofore described. The end of the shaft 70 at which the gear 75 is placed is preferably journaled in a second bearing 76. (Shown in Fig. 6.) A link 77 is carried by the crank 73, and this link at its outer end has a head 78 formed thereon, through which one end of a rod 82 is free to pass. This rod 82 is provided with a projection 81, usually of conical shape, as shown in Fig. 1, and this projection when the rod 82 is carried in direction of the crank-arm engages with the handle 80 of the valve 79 in the pipe 67 and opens the said valve, taking the handle 80 in the path of the head 78 of the link 77, so that as the shaft 70 continues to revolve the head 78 of the link 77 is brought in engagement with the handle 80, restoring the handle to its former position, closing the said valve 79 simultaneously, with the valve 69 being opened. The valves 62 and 69 are intended to make each a half-turn, while the valve 79 makes only a quarter-turn, which it makes, in one sense, when it opens, and, in the opposite sense, when it closes. The rod 82 is likewise journaled in a bearing 83 on the upright or standard 66, and a spring 84 is so connected with

the rod 82 as to exert pressure in a direction to open the valve 79 by bringing the projection 81 violently against the handle 80 of the valve; but the rod 82 is normally held from engaging with the handle 80 of the valve 79 by a projection 85 on the said rod 82 engaging with a latch 86 on a lever 87, which lever is fulcrumed upon a side of the frame, as shown in Fig. 1, and is held in its locking position by a suitably-applied spring 88. The rod 82 does not leave the head 78 of the link 77, because when the link moves in a direction which would tend to disengage the rod 82 the spring 84 acts to place the rod in position to open the valve 69, and consequently the free end of the rod 82 is made to extend some distance beyond the head of the link 77, insuring the rod remaining carried by the head of the link during all movements thereof.

The valve 69 is automatically or mechanically operated through the medium of a bevel-gear 89, provided with a toothed segment 89^a upon its flat or plain face, and this toothed segment is adapted to engage with the bevel-pinion 75, and said toothed segment 89^a on the gear 89 is of such length that it will give the plug of the valve 69 a half-turn, thus opening and closing the said valve. The gear 89 meshes with a large mutilated driving-gear 90, mounted on a shaft journaled in suitable bearings on the sides of the frame, and this driving-gear 90 is operated usually through the medium of a handle 91. The driving-gear 90 alternately meshes with the gear 89 and with a similar gear 93, which gear 93 is provided upon one of its faces with a mutilated section 94, adapted to engage with the pinion 65, connected with the plug of the valve 62, and when the mutilated section of the gear 93 is operating the valve 62 the mutilated section of the gear 89 is out of engagement with the pinion connected with the valve 69. A pulley 95 is mounted on the same shaft as the gear 93, as shown in Fig. 3, and this pulley is connected by a belt 96 with the gear or pulley 23, utilized to assist in raising and lowering the gathering-head. The pulley 95 is provided with two transversely-alining pins 97, and either of these pins is adapted to engage with the lever 18 for the purpose of withdrawing the bolt 16 from the upright of the gathering-head when the said head is to be raised or lowered, and a third pin 98 is carried by the gear 93 and is adapted at proper time to engage with the lever 87 and release the rod 82 from the catch 86, carried by said lever, and permit the projection 81 on the rod to open the valve 79.

A guide G is located below and at each side of the gathering-head C. The guides are duplicates and are rigidly attached to the frame by suitable supports 99. Each guide is provided upon its inner face with a lower longitudinal groove 100, an upper longitudinal groove 101, a connecting angular groove 102 at the rear, across which a gravity-latch 103 is placed, and a forward connecting-groove

104, the forward connecting-groove extending upward beyond the plane of the upper longitudinal groove 101. A screen 105 is adapted to travel in the grooves of the guides 5 G, and at the rear end of the said screen a brush 106 is located. The latch 103 acts as a switch and prevents the brush and screen from being withdrawn at the same elevation at which they were pushed under the gathering-head. The said screen is connected with a bar 107, held to slide in a hanger 108, projected downward from the frame, the rod 107 usually engaging with a friction-roller 109 in the said hanger. The forward end of the rod 107 is provided with a longitudinal slot 108^a, through which a pin 109^a is passed, which pin is likewise passed through an arm 110, which is pivoted at its upper end to the upper portion of the frame of the machine, as shown in 15 Fig. 1. The arm 110 is moved backward and forward, so as to carry the screen and brush backward and forward between the guides G through the medium of a link 111, pivotally attached to the said arm and to a wrist-pin 20 located on a pulley 112, which pulley is driven by a belt 113, that is carried over a second pulley 114, attached to the gear 89. When 25 the fruit is gathered by the nozzles 38 of the gathering-head by means of suction applied 30 to said nozzles, the said nozzles having been elevated, the screen 105 will travel in the lower grooves 100 of the guides G, and thence upward through the rear connecting-groove 102, since at that time the nozzles 38 will be 35 relieved from suction and the fruit will drop therefrom onto the screen. When, however, the screen reaches the upper grooves 101, as shown in Fig. 3, the brush 106 will be in position to engage with all of the nozzles 38 as 40 the screen is drawn outward from the guides, thus clearing the said nozzles from any foreign matter that may adhere thereto, and, as shown in dotted lines in Fig. 1, when the rear or brush end of the screen travels in the upper portion of the rear end connecting-grooves 45 104 the screen 105 will be given such an inclination that the fruit on the screen will roll into a box or receptacle 115, placed to receive it, as shown in Fig. 1.

50 With reference to the floating valves 44 in the tubes 36 it is more particularly explained that said valves serve to prevent the air from filling the vacuum - cylinder by rushing through those gathering-tubes 36 which have 55 not attracted prunes. When suction is applied to the gathering-tubes 36, each tube must be closed by some means, else the vacuum-cylinder would soon be filled with air. Those tubes 36 that descend properly on 60 prunes will be closed by the prunes attracted; but should a tube 36 descend upon the rough surface of a chip or a stone, for example, the air may not be excluded from said tube 36 by the article attracted, and when suction is 65 applied such air as the chip or stone cannot exclude drives the float-valve 44 to the upper end of such gathering-tube and the valve will

close the small opening 43 in the upper end of the tube. The floating valves 44 or their equivalents are essential, since without them 70 the vacuum could not be secured long enough to raise the prunes and drop them upon the screen 105 unless each tube 36 should gather a prune at each operation, which is not likely, as prunes do not completely cover the ground 75 under the trees. The elastic sleeves 37 render the proper contact between the nozzles and the prunes more certain, as said elastic sleeves enable the nozzles to accommodate themselves to the position of the prunes when 80 the gathering-tubes 36 are carried downward. It will be understood that the driving-wheel 90 may be turned in an opposite direction to that indicated in the drawings, if found desirable. 85

When the machine is in operation, one attendant will drive the machine to the proper position beside or beneath a tree. The attendant upon the machine will then manipulate the pumps producing vacuum and compression, while a second attendant upon the ground moves the valve mechanism until the gathering-head is over a group of prunes and adjusts the head to the prunes. 90

In the operation of the machine the compressed-air valve 62 should be opened, whereby the suction or gathering tubes 36 are forced downward to the fruit. This valve is then closed and the rarefied-air valve 79 is opened through the action of the rod 82, 100 which is released from the lock-lever 87 when the compressed-air valve 62 is closed. This rarefied-air valve 79 is abruptly opened, and the suction thereby produced in the lower chamber or duct 30 causes the prunes to be 105 drawn to the ends of the tubes 36 and the floating or sliding valves of the tubes 36 that do not carry prunes to rise. When the rarefied-air valve 79 is opened, the compressed-air valve 62 must be closed, and at that time 110 the upright 13 of the gathering-head is released from its latch 16 and said head is raised and relocked in its elevated position. The brush and screen must at this time be pushed under the gathering - head, as has 115 been described, and the rarefied-air valve 79 is thereupon closed, which causes the prunes to drop to the screen, as has been stated. At the time that the rarefied-air valve 79 is closed the second rarefied - air valve 69 is 120 opened. This action, by creating suction in the upper duct or chamber 27 of the gathering - head, causes the suction or gathering tubes 36 to be drawn upward, bringing their lower ends in the same plane. The rarefied- 125 air valve 69 is then closed and the brush and screen are drawn from under the gathering-head, thus brushing the nozzles or lower ends of the suction-tubes and rolling the prunes off the screen into a receptacle placed to receive them. 130

Having thus described our invention, we claim as new and desire to secure by Letters Patent—

1. In a device for gathering prunes and other fruits from the surface of the ground, a series of movable gatherers pneumatically controlled by alternately-applied compression and suction.

2. In a device for gathering prunes and other fruit from the surface of the ground, a series of movable gatherers pneumatically controlled by applied compression and suction, 10 guides for the same, a mechanism for effecting a vacuum and a compression of air, conductors between the vacuum and compressing sections of said mechanism, and means for controlling the supply of compressed air and the suction.

3. In a device for gathering prunes and other fruit from the surface of the ground, a series of movable gatherers pneumatically controlled by alternately-applied compression 20 and suction, guides for the gatherers, pneumatically-controlled valves loosely mounted in said gatherers, an air-compressing and vacuum mechanism, and a controlling mechanism between the compressing and the vacuum compartments of said pneumatic mechanism and the gatherers.

4. In a device for gathering prunes and other fruit from the surface of the ground, a series of movable gatherers pneumatically controlled by alternately-applied compression and suction, guides for the gatherers, pneumatically-controlled valves loosely mounted in said gatherers, an air-compressing and vacuum mechanism, tubular connections between the compressing and vacuum compartments of said mechanism, valves located in said connections, and means for closing one valve as another is opened.

5. In a device for gathering prunes and other fruit from the surface of the ground, guides for the tubes, and means, substantially as described, for pneumatically raising and lowering the tubes, attracting the fruit to said tubes and releasing the fruit therefrom.

45 6. In a device for gathering prunes and other fruit from the surface of the ground, a series of gathering-tubes, guides for the tubes, means, substantially as shown and described, for pneumatically raising and lowering the tubes, attracting the fruit to the tubes and releasing the fruit therefrom, and suction-controlling valves mounted to slide in said tubes, for the purpose specified.

55 7. A device for gathering prunes and other fruit from the surface of the ground, consisting of an adjustable gathering-head, devices for raising and lowering the said head and maintaining it in adjusted position, gathering-tubes having guided movement in said head, and means for pneumatically raising and lowering the gathering-tubes, attracting fruit to the tubes and releasing the fruit therefrom.

8. In a device for gathering prunes and other fruit, a series of gatherers, a screen mounted 65 to reciprocate beneath the gatherers, guide-ways for the said screen, and a brush carried

by said screen, the screen being adapted to receive the fruit from the gatherers and the brush to clean the fruit-receiving surfaces of the gatherers, as described.

9. In a machine for gathering prunes and other fruit, a gathering-head provided with a series of gathering-tubes, and means for pneumatically attracting the fruit to said gatherers and releasing it therefrom, guides located 70 at each side of the gathering-head, provided with upper and lower grooves in their inner surfaces, said grooves being connected at their ends, and a screen mounted to slide in the said grooves, for the purpose specified. 80

10. In a machine for gathering prunes and other fruit from the surface of the ground, the combination, with a gathering-head provided with a series of gathering-tubes, and means for pneumatically attracting fruit to 85 said tubes and for discharging the fruit therefrom, of a guide located at each side of the gathering-head independent thereof, each guide being provided with an upper and a lower slideway, the slideways of each guide 90 being connected at both ends, a gravity-latch located at one end connection of the said slideways, the other end connection extending beyond the plane of the upper slideway, a screen held to travel in the said slideways, 95 and a brush carried by the said screen, as described.

11. In a device for gathering prunes and other fruit from the surface of the ground, a gathering-head provided with a central chamber and an upper and a lower duct or channel, tubes extending through the body-chamber from one duct or channel to the other, tubular gatherers loosely mounted in the said guide-tubes and extending beyond the lower 105 surface of the gathering-head, an air-compressing and vacuum mechanism, and a connection between the air-compressing compartment of said mechanism and the upper duct, connections between the vacuum-compartment of said mechanism and the upper and lower ducts or channels, the said connections being provided with valves, and devices for closing one valve as a second is opened, as 110 described. 115

12. In a device for gathering prunes and other fruit from the surface of the ground, the combination, with a gathering-head provided with a central compartment, an upper and a lower duct, and guide-tubes extending 120 from the upper to the lower duct through the central compartment and from the lower duct downward beyond the bottom of said head, of gathering-tubes loosely mounted to slide in said guide-tubes, each gathering-tube being provided with an aperture at its top, a flexibly-connected nozzle at its bottom and a piston connected with its upper end, the pistons being in close engagement with the inner faces of the tubes, extending within the 125 body-chamber of the gathering-head, valves mounted to slide in said tubes, an air-com-

pressing and vacuum-producing mechanism, a tubular connection between the compressing-compartment of said mechanism and the upper duct in the gathering-head, and independent tubular connections between the vacuum-chamber of said mechanism and the upper and lower ducts, and valves located in said tubes, the valve of one tube being adapt-

ed to be closed when the valve of another tube is opened, for the purpose described. 10
